UNITED STATES PATENT OFFICE

2,481,913

STATIC ELECTRICITY DISCHARGING DEVICE

William J. Duchesneau, Hartford, Conn.

Application September 14, 1946, Serial No. 697,028

2 Claims. (Cl. 175—264)

1

The present invention relates to static electricity discharging devices, and more particularly to a device adapted to be positioned in a road to discharge or release accumulated static electricity from the frame and/or body of a vehicle passing thereover.

As is well known, automobiles, trucks and other vehicles of the type which are mounted on rubber tires, under certain atmospheric and ground conditions, tend to build up a substantial charge of static electricity within their bodies. Such charges of static electricity are particularly undesirable when the vehicle subsequently becomes grounded through the body of persons in contact with the vehicle. This is particularly noticeable at toll houses, for example, where the driver of the vehicle, when passing a coin to the toll collector, grounds the body of the vehicle through himself and the collector resulting in a substantial shock to both persons.

It is an object of the present invention to provide a device which may be installed in the road ahead of the toll house or other place where discharge of accumulated static electricity is desired for the purpose of grounding the vehicle and thereby releasing or discharging the static electricity accumulated therein.

It is a further object of the invention to accomplish the foregoing object by means of a device which will not be susceptible to breakage even when the wheel of a vehicle may pass directly thereover.

A further object of the invention is to provide a device of the character described which can be readily assembled and disassembled and can be easily kept in a clean and efficient operating condition.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Figure 1 is a cross sectional side view showing the device installed in a concrete road;

Fig. 2 is a cross sectional end view of the device positioned in a concrete road; and

Fig. 3 is a cross sectional end view of the cover taken along the line 3—3 of Fig. 1.

Referring to the drawing, the device constructed in accordance with the invention comprises a receptacle 10 which, in the specific em-

2

bodiment shown, is a metal box-like structure and is adapted to be set into the surface of a road, such as the concrete pavement 11. In the preferred embodiment shown, the upper edge of the receptacle 10 is permitted to extend slightly above the surface of the concrete pavement 11. Fixed to the bottom of the receptacle 10 is an electrical conducting stake or post 12 extending downwardly into the ground 13 thereby effectively grounding the receptacle 10.

Supported in guideways 14, adjacent the upper edge of the receptacle 10 and positioned about midway of the receptacle, is a metallic spindle 15 provided with flanges 16 spaced from the ends thereof.

Received through a hole 17 in the spindle 15 is a flexible conducting rod 18 which is adjustably secured to the spindle 15 by means of the set screw 19. The lower end of the rod 18 has mounted thereon a weight 20 which acts to bias the rod into an upright position.

A cover 21, having tapered edges 22, is provided to be placed over the receptacle 10. In the preferred embodiment, the cover 21 has a groove 23 extending therearound to receive the upper edge of the receptacle 10, thus acting to seal the receptacle at the edges against dirt and moisture.

Extending centrally from the midpoint of the cover 21 in the direction of passage of a vehicle is a slot 24 in which the rod 18 may move during normal pivoting movement. In the event that a car wheel should pass directly over the rod 18, there is provided a groove 25 extending outwardly from the slot 24 adapted to receive the end of the rod 18 and to position it substantially flush with the cover 21 thereby preventing breakage of the rod.

Inasmuch as some dirt and water can enter the device through the slot 24, there is provided a removable pan 26 which is set into the receptacle 10 so as to encompass the slot 24 as well as flanges 16 on the spindle 15. It has been observed that water deposited on the spindle 15 will drop off at the flanges 16 and will not be carried to the extremities of the spindle, whereby the water does not reach the inner surfaces of the receptacle 10. In order to remove the pan 26 for periodic cleaning of the device, it is necessary only to remove the cover 21 and to lift out the spindle 15 whereupon the pan 26 may be readily withdrawn.

Inasmuch as it may not be desired to utilize the device during certain winter months when static electricity accumulations in motor vehicles

do not present much of a problem, the device can be readily conditioned for non-use by removing the cover 21 and the rod 18 (also the spindle 15, if desired) and substituting a cover similar to the cover 21 except that it is imperforate. The device is thus protected against the accumulation of dirt and moisture and will require no further attention until it is again desired to place the device in operating condition.

In light of the above disclosure, it will be seen that, in accordance with the present invention, there is provided a static electricity discharging or releasing device which will have little tendency to break even over long periods of usage. In general, the vehicle passing over the device merely pivots the rod 18 on the spindle 15 without materially flexing the same and, even though the wheel of the vehicle should pass directly over the rod, there still will be only a moderate flexing of the rod without the occurrence of any breakage. The device is effective in operation and in no way interferes with the normal usage of the road.

In view of the specific description given above of a preferred embodiment of the invention, it will be possible for one skilled in the art to make various modifications and variations in the construction of the device without departing from the spirit of the invention, and all such variations and modifications are intended to be included within the scope of the following claims.

I claim as my invention:

1. A device for discharging static electricity from vehicles comprising a metal receptacle for placement in the surface of a road, an electrically conducting, horizontal spindle, electrically conducting bearing means adjacent the top of the receptacle rotatably supporting the ends of the spindle therein and electrically interconnecting the spindle and receptacle, a flexible electrically conducting rod adjustably fixed on the spindle in angular relation thereto and rotatable therewith, means biasing the rod into upright position,

and a cover extending over the receptacle and covering said bearing means and having a centrally located slot through which the rod extends, permitting pivoting movement of the rod with the spindle.

2. A device for discharging static electricity from vehicles comprising a metal receptacle for placement in the surface of a road, a removable pan positioned in the bottom of the receptacle, an electrically conducting, horizontal spindle, electrically conducting U-shaped bearings adjacent the top of the receptacle rotatably supporting the ends of the spindle therein and electrically interconnecting the spindle and receptacle, a flexible electrically conducting rod fixed to the spindle in angular relation thereto and rotatable therewith, means biasing the rod into upright position, and a cover extending over the receptacle and covering said bearing means and having a centrally located slot through which the rod extends for permitting pivoting movement of the rod with the spindle.
